HOLDER FOR ARTICLES

Oscar Leonard Swanson, Erie, Pa.

Application June 27, 1944, Serial No. 542,306

4 Claims. (Cl. 312—112.5)

1

This invention relates to an improved holder for tooth brushes or similar articles, and more particularly to a holder having a closure movable into an opened or closed position.

It is a purpose and object of the invention to provide a tooth brush holder of such structure and design as to be conveniently attachable to a wall, a cover being provided which, when in closed position, encloses the holder and any tooth brushes mounted thereon.

It is also an object of the invention to provide a holder having a support member and cover so related that, with the cover in closed position, apertures are provided, top and bottom, by which to give free circulation of air to enable rapid drying of the brushes.

Another object of the invention lies in the provision of an individual sanitary compartment for each brush that may be positioned in the holder.

An additional object of the invention appears in the provision of a cover which, when moved into closed position, not only fully encloses the tooth brushes, but also serves to prevent inadvertent displacement thereof.

Another and most important object of the invention lies in the provision of a holder having a cover so mounted on the body of the holder as to be movable, under spring pressure, into a closed position against the compartment divisions, and stop means to determine the extent to which the cover may be moved, also under spring action, into an opened position.

Other advantages and objects of the invention will be more fully understood from a consideration of the following specification, taken in conjunction with the accompanying drawing, in which

Fig. 1 is a front elevational view of one embodiment of the invention, parts being broken away to disclose certain of the structural details, as well as the position of a tooth brush when mounted in the holder;

Fig. 2 is a horizontal sectional view taken substantially on the line 2—2 of Fig. 1;

Fig. 3 is a vertical transverse sectional view taken substantially on the line 3—3 of Fig. 1;

Fig. 4 is a further vertical transverse sectional view taken substantially on the line 4—4 of Fig. 1;

Fig. 5 is a sectional view taken substantially as

indicated for Fig. 4 and shows the cover in fully opened position;

Fig. 6 is a fragmentary exploded perspective view illustrating the assembly of the parts of the holder;

Fig. 7 is an enlarged fragmentary view of the pivot details shown in Fig. 3; and

Fig. 8 is an enlarged fragmentary view of the pivot structure as shown in Fig. 5.

10 Referring more particularly to the drawing, the reference numeral 10 is employed to generally designate a holder embodying one form of the invention. The holder comprises a body member 11 and cover 12. The member 11 includes a back 13, from one face of which partitions 14 extend. These partitions may be uniformly spaced, as shown, and extend from the bottom edge of the back upwardly to adjacent the top edge, terminating just short of a bead 16 formed along the upper edge of the back. The forward upper edges of the partitions 14 are preferably rounded, as at 11, for a purpose hereinafter set forth. At the bottom of certain of the intermediate partitions is a brush support 18, so shaped as to provide an opening 19 and a passageway 21 between one side thereof and the next adjacent partition 14. In the present disclosure the holder is shown adapted to accommodate five brushes, such as indicated by the brush 20 in Fig. 1, and the three intermediate compartments are defined by the partitions 14, back 13, and the cover 12 when in closed position. The end compartments are formed by only one partition, a part of the back 13, and a portion of the side and front of the cover when in closed position. Furthermore, brush supports 22 for these end compartments are of somewhat different shape, being designed to conform to the cover contour. However, each of the supports 22 includes a portion that cooperates with an adjacent partition 14 to provide a passageway 25 for a part of the handle of the brush 20. The bead 16, in the present disclosure of the invention, is interrupted midway of its length by a recess or slot 23. The base wall 24 of the recess is formed in a predetermined curve and terminates in a cut-back shoulder 26 that constitutes a seat for one end of a C-shaped spring 27.

45 The cover 12 comprises a top 28, front wall 29, and end walls 31. In the present instance the

front wall 29 is slightly curved and, through suitable rounded portions, blends with the end walls 31 and the top 28. It will be noted that the partitions 14, as well as the brush supports 18 and 22, are proportioned to conform to the contour of the cover.

Depending from the top wall 28 of the cover are short partitions 32. These partitions are so disposed and contoured as to abut and complement the partitions 14, when the cover is in closed position, to complete the compartments. At the rear of each partition 32 is an arcuate recess that is complementary to the bead 16, and it is these recesses, together with a rear cover portion 33, that constitute the bearing points for the cover 12. In this connection it will be noted that with the provision of a multiplicity of bearing points located uniformly along the upper edge of the back 13, there can be little or no twisting of the cover during pivoting into one position or another. Centrally of the portion 33 is a recess 34, the base wall 36 of which is formed in a predetermined curve and terminates in a shoulder 37. Walls 24 and 36 are complementary, when the cover 12 is in opened position, to form a seat for the body of the spring 27 and, of course, the shoulder 37 serves to seat the other end of this spring. With the cover in opened position, as shown in Fig. 5, it is evident that the spring can neither be readily dislodged nor can the cover be forced to a further opened position.

To conveniently mount the holder, a block 38 is attached to or formed integral with the base 13 and extends rearwardly therefrom. This block is formed with a downwardly opening groove 39, the sides of which are undercut to receive and hold a plate 41 that may be attached directly to a wall by means of a screw 42. The upper end of the block may terminate at a point such that when the cover assumes a fully opened position, an edge of portion 33 will abut the block and thus additionally safeguard against breakage or damage due to careless manipulation of the cover from closed to opened position.

Inasmuch as the top 28 of the cover has contact with the base only along the partitions 32, a narrow aperture 43 is created between the cover and the base, and this aperture cooperates with the aperture in either brush support 18 or 22 to provide free circulation of air lengthwise of each compartment. It may be observed that no top aperture 43 appears in the center compartment. This compartment may be disregarded as a brush holder, if desired, or the partitions thereof may be close together or solid and, if solid, cut away to an extent to provide space for a spring seat. Due to the predetermined location of the complementary pivots of the bead 16 and partitions 32, together with the location of spring seats 26 and 31, the C-shaped spring 27 serves to yieldingly hold the cover in closed position and has a dead center approximately midway between closed and opened position of the cover. Thus, when the cover is moved into opened position past dead center of the spring, it will be yieldingly held in the position shown in Fig. 5.

It will be particularly noted that each compartment is adapted to receive and support a tooth brush in such a manner that the bristles thereof are in line with the top and bottom apertures of the holder by reason of which it is believed more rapid drying of the brush may take place. Furthermore, the brush 20 is placed in

the holder in a sidewise manner and, when the cover 12 is moved into closed position, the front wall 29 of the cover serves to complete the brush compartment and secures all brushes against inadvertent displacement.

Although applicant has shown and described only one modification of his invention, it will be apparent to those skilled in the art that variations thereof may be made without departing from the spirit and scope of the invention as defined in the annexed claims.

Having thus set forth my invention what I claim as new and for which I desire protection by Letters Patent is:

1. A holder for articles comprising a body portion, partitions on one face of said body portion defining vertically extending compartments, article supports adjacent the base of said body portion cooperating with said partitions to provide passages for entry of said articles into said compartments, a cover for said holder, said cover including a top for closing the upper ends of said compartments, a front portion for closing the fronts of said compartments and said passages, and end portions cooperating with certain of the partitions to form additional compartments when said cover is closed, complementary pivotal means formed integral with said body portion and cover, spring means securing said means in operable pivotal relationship, said spring means also effecting holding of said cover in closed position whereby to secure articles in said holder against inadvertent displacement.

2. In a holder for articles, a body portion and cover, partitions on one face of said body portion defining vertically extending compartments, further partitions on said cover, complementary pivotal means on said body portion and cover, spring means securing said means in operable pivotal relationship and effecting holding of said cover in opened or closed position, the partitions of said body portion and cover cooperating to provide compartments extending the full height of said holder when said cover is in closed position and ends on said cover cooperating with certain of the partitions of said body portion and cover to form additional compartments when said cover is closed.

3. In a holder for articles, a body portion and cover, partitions on one face of said body portion, article supports adjacent the base of said body portion cooperating with said partitions to provide passages for entry of said articles into compartments formed by adjacent partitions, said cover including a top, partitions on said top, complementary pivotal means on said body portion and the top partitions, spring means securing said complementary means in operable pivotal relationship, a front portion of said cover being adapted to close the fronts of said compartments and said passages, and ends on said cover cooperating with certain of the partitions of said body portion and said top to form additional compartments when said cover is in closed position.

4. In a holder for articles, a body portion and cover, partitions on one face of said body portion, article supports adjacent the base of said body portion cooperating with said partitions to provide passages for entry of articles into compartments formed by adjacent partitions, complementary pivotal means on said body portion and said cover, spring means securing said complementary means in operable pivotal relationship, said cover including walls adapted to en-

close the top, front, ends, and partitions of said body portion, the end walls of said cover cooperating with certain of the partitions and article supports to provide additional compartments when said cover is closed, partitions in said cover complementary to the partitions of said body portion, all of said partitions cooperating to provide compartment walls extending the full height of said holder within the vertical confines of said cover.

OSCAR LEONARD SWANSON.
